[57] CLAIM

The ornamental design for outer casing mounted around a suspension rod, as shown and described.

DESCRIPTION

FIG. 1 is a perspective view of a outer casing mounted around a suspension rod showing my new design;

FIG. 2 is a top plan view thereof;

FIG. 3 is a bottom plan view thereof; and,

FIG. 4 is a front elevational view thereof; the opposite side being a mirror image of the shown; and is a left side elevational view thereof; and the right side being a mirror image of that shown.
